PROCESS FOR THE PRODUCTION OF POTASSIUM AND MAGNESIUM SULFATE DOUBLE SALTS

Hans Autenrieth, Hannover, Germany, assignor to Vef-kaufsgemeinschaft Deutscher Kaliwerke G.m.b.H., Hannover, Germany, a corporation of Germany.

Application October 20, 1955, Serial No. 541,786

21 Claims. (Cl. 23—117)

The present invention relates to a novel method for the production of potassium and magnesium sulfate double salts. More particularly, the invention relates to a process for the production of hydrates of double salts of potassium and magnesium sulfate, both, starting from initial materials either containing sodium chloride or free of sodium chloride, and, simultaneously therewith, the recovery of substantial quantities of magnesium chloride from the double salt conversion solutions.

It is well known that in the production of potassium and magnesium sulfate double salts, the higher the content of magnesium chloride within the solutions used to obtain the double salts, hereinafter referred to as conversion solutions, the larger will be the output of the double salt itself. In addition, it is well known that a relatively high content of magnesium chloride in such conversion solutions will make for a more economical over-all process, since magnesium chloride itself can be recovered and used for the manufacture of magnesium oxide and hydrochloric acid. Thus, the art recognizes on the one hand the necessity for obtaining higher yields of the double salts themselves, and, on the other hand the desire to obtain a conversion solution possessing a high content of magnesium chloride.

With respect to prior known processes, the usual yield of the double salt, calculated on the basis of K_2O , varies from approximately 63—78% of theoretical. At the same time, it has been possible to produce conversion solutions containing magnesium chloride in a content of approximately 38—45 mols/1,000 mols of H_2O at best, which corresponds to 185—205 g./l. $MgCl_2$.

One object of the present invention is the production of double salts of potassium and magnesium in better yields than it was heretofore possible.

Another object of the invention is the production of said double salts from solutions containing sodium chloride (saturated or not saturated) in better yields than was heretofore possible.

A third object of the invention is the recovery of a mother liquid having a substantially higher concentration of magnesium chloride from conversion solutions used in the production of such potassium-magnesium double salts.

These, and further objects of the invention will become apparent in the description thereof, read in conjunction with the drawings, in which:

Fig. 1 is a graph showing various bands of isotherms of saturation of the system $K_2Cl_2 + MgSO_4 \rightleftharpoons K_2SO_4 + MgSO_4$ at stable and meta-stable solubilities in accordance with the invention, excluding the presence of sodium chloride; this graph represents at any point complete saturation with potassium chloride; and

Fig. 2 is a graph similar to Fig. 1, but including the

2

presence of sodium chloride, i.e. in the whole graph exists complete saturation not only with potassium chloride but also with sodium chloride.

The methods for the graphical representation of complex salt systems were developed by D'Ans: "Die Lösungsgleichgewichte der Systeme der Salze ozeanischer Salzablagerungen," Berlin, 1933, pages 13—44. Also the method of the "Parallelprojektion" is given there, p. 32 and following. Our graphs are "cuts" 5 through the three dimensional representation of the isotherms, as it is described by D'Ans on "Untersuchungen über die metastabile Löslichkeit in Systemen der Salze ozeanischer Salzablagerungen," Kali 38 (1944), pages 42—49, 69—73, 86—92.)

As contrasted with prior conventional procedures as outlined above, in accordance with the instant invention, it is now possible to obtain yields of the double salt calculated as K_2O of 89% and above, which is an increase of at least 10—25% as compared with prior conventional processes. At the same time, the yields of magnesium chloride obtained from the conversion solutions range correspondingly exceedingly higher, i.e., 10 50 and above mols/1,000 mols of H_2O corresponding to well over 200 g./l. $MgCl_2$.

In order to better understand the operation of the instant invention, reference is made initially to Fig. 1 of the drawing. As is stated thereon, the solid lines relate to stable conditions of equilibrium, while the dotted lines and dashed lines relate to meta-stable conditions of equilibrium.

A system consisting of a solution and one or more sediments is called stable if, provided that external conditions remain unchanged, the composition of the solution and of existing sediments does not change even 20 during an infinite period of time.

A system consisting of a solution and one or more sediments is called meta-stable if the solution is oversaturated with one or several salts and if this or these salts which exist in oversaturation in the solution, do not occur as sediments; instead one or several others, which at a given temperature and given conditions of concentration are not in a thermodynamic equilibrium but for kinetic reasons exist during shorter or longer periods of time, occur as such sediments. Although these meta-stable sediments are gradually converted to stable ones, this may take rather a long time so that for industrial purposes such meta-stable systems may often be treated like stable systems. Whether this is 30 possible or not depends on kinetic conditions to which our invention also attaches paramount importance.

Referring in the first instance to the production of schoenite ($K_2SO_4 \cdot MgSO_4 \cdot 6H_2O$) from potassium chloride and magnesium sulfate and hydrates thereof at a conversion temperature of 15° C., it should be possible to attain the stable point of equilibrium indicated by M_{15}^0 , which is shown on Fig. 1 and at which point KCl , schoenite and Epsom salt ($MgSO_4 \cdot 7H_2O$) will co-exist, and further, at which point the conversion solution should have a content of 50.7 mols of $MgCl_2$ /1,000 mols of H_2O corresponding to 241 g./l. $MgCl_2$. Further, for example, on the 25° isotherm of schoenite, the point K_{25}^0 should be obtainable, at which point KCl , schoenite, leonite, and kainite should be in co-existence, while, at 40 the same time the conversion solution should contain 52.0 mols of $MgCl_2$ /1,000 mols of H_2O (243 g./l. $MgCl_2$). The metastable solubility of leonite and the stable solu-

bility of schoenite converge at this point. Also the kainite forms a stable solid phase at this point (line of solubility of kainite for this temperature is not drawn). The same applies to KCl: four salts point.

As is quite obvious, the amounts of $MgCl_2$ described above with respect to points M_{15} and K_{25} are in fact greater than any amounts of $MgCl_2$ attainable in conversion solutions in accordance with prior procedures. The relatively high contents of magnesium chloride in conversion solutions has not been attainable in prior art processes, however, because of the fact that the hydrated magnesium sulfate employed in the production of the double salt possesses an extremely slow dissolution rate at the given temperature when approaching its saturation point of solubility. Thus, if it were sought to saturate the solutions with hydrated magnesium sulfates in order to produce the double salt at the required temperature as shown on the isotherm, the time required for the reaction would make the process economically and practically impossible.

In addition, were an excess of hydrated magnesium sulfates thereof applied at the given temperature in order to accelerate the conversion, the result would necessarily be an excess of Epsom salt in the double salt itself, which is recovered, thus seriously affecting the purity of the double salt, and, in fact, preventing this mode of operation.

In accordance with the instant invention, however, it was discovered that in the system of the salt pair $KCl + MgSO_4 \rightleftharpoons K_2SO_4 + MgCl_2$ it was possible to attain the various points of equilibrium on the isotherms, as, for example, the stable point of equilibrium M_{15}^0 without the necessity of an overly long period of time expended in dissolving hydrated magnesium sulfate on the one hand or the use of a large excess of hydrated magnesium sulfate on the other hand. In accordance with the invention, moreover it is now possible to carry out the conversion of the potassium chloride and hydrated magnesium sulfate into the double salt in the meta-stable field exclusively, wherein it is possible to obtain conversion solutions having an exceedingly high content of magnesium chloride.

Thus, the process of the application in general contemplates the reaction of Epsom salt with potassium chloride carried out at a temperature sufficiently high so that, in accordance with the graphs set forth in Figs. 1 and 2, the conversion solution will not be saturated with Epsom salt. The double salt formed during the reaction already segregates during this process and after all the Epsom salt is completely dissolved, the solution is cooled down sufficiently to precipitate further quantities of the double sulfate of potassium and magnesium therefrom, and thus, in fact, the desired point of equilibrium in which the potassium chloride, the Epsom salt, and for example, the schoenite, co-exist, is attained. The precipitation of KCl and Epsom salt takes place only, when the temperature of the solution becomes lower than the temperature for which the initial quantities are calculated. In consequence the desired double salt is recovered in the particularly pure form, since there will be no surplus of Epsom salt or potassium chloride therein, and, at the same time the conversion solution is saturated with KCl, Epsom salt and the double sulfate, and very substantial quantities of magnesium chloride may be recovered from the conversion solutions and further used for various chemical processes.

Referring for the moment to Fig. 1, it is seen that isotherms for schoenite at 15, 25, 30, and 35° C. are given and, at the same time, isotherms for Epsom salt within the same temperature range are given. Attention is called to the line formed by connecting the points of connection of the schoenite and Epsom salt isotherms of similar temperature. This line, the polytherm so formed, is classified as a line of co-existence of

in the temperature range from 15 to 35° C., and is repre-

sented in Fig. 1 by the line connecting the points M_{15}^0 , $M_{22.5}^0$, M_{25}^0 , M_{30}^0 , and M_{35}^0 .

Similarly, in Fig. 1 lines of solubility are shown for the double salt leonite ($MgSO_4 \cdot K_2SO_4 \cdot 4H_2O$), which does not appear as solid phase below 25° C. While the lines of the metastable solubilities are represented for 25°, 30° and 35° C. (dotted lines), from the stable solubilities only that for 35° is given (full line). By connecting the points of intersection of the isotherms of leonite on the one hand and the isotherms of Epsom salt on the other hand (points L_{25} , L_{30} , L_{35}) the line of coexistence of $KCl + \text{leonite} + \text{Epsom salt}$ within the temperature range of 25–35° could be obtained in the same manner as the schoenite line (leonite line not drawn in Fig. 1). Similarly, therefore, when seeking to produce leonite, the reaction solution is cooled down to a point for which the quantities of initial ingredients are calculated with the leonite thereupon being recovered from the reaction solution. The double salt leonite, which is recovered in this manner, is, by the same reason as with schoenite, as described above, of a particularly pure quality, since there is no excess of either Epsom salt of KCl therein.

The saturation lines of kainite have been omitted (except the 22.5° C.-isotherm) from Fig. 1, since within the practical field of operation as set forth therein kainite will have only a very low rate of formation, and thus does not come into question in the separation of the double salt.

As may be seen from Fig. 1, at a conversion temperature of 30–40° C., one would operate within a field wherein schoenite is in a meta-stable solid phase. Under these conditions, the stable solid phase (within the particular temperature range) is the leonite. However, leonite has a much lower rate of formation than schoenite, so that under these given conditions, only schoenite will be segregated and separated.

In addition, the stable point of equilibrium K_{25} , which represents a point of co-existence of $KCl + \text{leonite} + \text{schoenite} + \text{kainite}$, may be obtained in accordance with the invention by at first carrying out a conversion with prescribed quantities of KCl and hydrated magnesium sulfate as would be theoretically required to obtain the point K_{25} within the temperature range of about 30–40° C. After the hydrated magnesium sulfate has been dissolved, a cooling of the reaction solution to a temperature of about 25° C. would take place, and the desired results obtained.

As is quite evident, Fig. 1 shows the additional possibility of obtaining meta-stable conversion solutions which have exceedingly high contents of magnesium chloride. For example, the conversion solution obtainable at the point M_{25}^0 , which is a saturation of $KCl + \text{schoenite} + \text{Epsom salt}$ at a temperature of 25°, is readily obtainable without any particular difficulty, even though the conversion solution at this point is super-saturated with leonite and kainite. Under the conditions prevailing, however, both solid phases of leonite and kainite present in supersaturation have such an insignificant tendency of formation, i.e., tendency to precipitate and/or segregate, that they cause no difficulty whatever and a very pure double salt without any admixture of Epsom salt and KCl is obtainable. The conversion solution at point M_{25}^0 has a content of magnesium chloride, on the other hand of 54.7 mols/1,000 mols of H_2O , which corresponds to 256.5 g./l. $MgCl_2$. Similarly, when operating with an equilibrium solution at M_{30}^0 , a highly purified double salt without admixture of Epsom salt and/or KCl is obtainable, and at the same time a content of magnesium chloride in the conversion solution of 56.0 mols/1,000 mols of H_2O , corresponding to 260 g./l. $MgCl_2$, may be recovered.

It may be further seen from Fig. 1 that the points of co-existence, L_{25}^0 , L_{30}^0 , and L_{35}^0 , in which KCl, leonite and Epsom salt co-exist, are situated within a particularly desirable range with respect to $MgCl_2$ recovery, since the

conversion solutions within this range show a much higher concentration of $MgCl_2$ than any of the previous mentioned conversion solutions. In order to obtain these highly desirable magnesium chloride solutions along with the simultaneous production of a desirable double sulfate, it is important to provide that leonite and not schoenite is obtained as the double salt, and, at the same time, that the stable solid phase kainite, which is in supersaturation along this range, does not segregate with the leonite.

It has been found that the segregation of kainite in a system free from sodium chloride will either not occur or may be easily prevented within a temperature range up to about 55° C. It has been found that within such a system, the formation of leonite will take place at temperatures of about 45–55° C., while in the temperature range below from about 40–45° C., schoenite will be separated exclusively.

Thus, in order to obtain the conversion solution at the point L_{30}^0 , with its magnesium chloride content of 61.1 mols/1,000 mols of H_2O , corresponding to 285 g./l. $MgCl_2$, one would stir at temperatures of about 45–55° C. quantities of Epsom salt, or other hydrated magnesium sulfate, potassium chloride, and water, as would be theoretically required for the double salt conversion. After the Epsom salt has been dissolved, the solution should be cooled to about 30° C. At first, the conversion will proceed within the temperature range of about 45–55° C., wherein only leonite is formed. When there is a cooling down to about 30° C., the magnesium sulfate in solution reacts with the remaining potassium chloride present, and further quantities of leonite are segregated. The presence of the solid leonite formed in the solution at the temperature between about 45–55° C., causes that also at temperatures below 45° exclusively leonite and at no time schoenite is segregated. In this manner, the equilibrium solution L_{30}^0 is attainable and, at the same time, a completely pure double salt (leonite) is recovered.

It is possible to operate within the entire range L_{25}^0 – L_{35}^0 and to recover the magnesium chloride conversion solution all along this range. However, when operating here, it should be noted that from a practical standpoint it is not expedient to attempt to produce conversion solutions having contents of magnesium chloride much higher than the content present in the L_{30}^0 solution, because when working above this point, there is ever present an imminent danger of kainite formation.

In addition, in this operation as with the various other operations in accordance with the invention, in place of water in the formation of the conversion solution, i.e., Epsom salt, potassium chloride, and water as prescribed above, it is possible to employ a quantity of a solution equivalent to the theoretical quantity of water required, this solution having present a low content of magnesium chloride, which solution may be obtained, for example, from various chemical manufacturing processes, including conventional processes for the production of double sulfates wherein a solution with a low content of magnesium chloride would be present.

The various systems as discussed above in conjunction with Fig. 1, relate to a system free of sodium chloride, i.e., the supposition that all starting products used in the conversion are free of $NaCl$. In fact, it is well known that the cost of sodium chloride-free potassium chloride is far in excess of potassium chloride having a certain content of sodium chloride therein. In fact, the purity of commercial potassium chloride will not permit its use in the system free of sodium chloride as described in Fig. 1. In view of this, an analogous figure to Fig. 1, i.e., Fig. 2, was prepared, which shows the conditions of solubility of sulfate salts within the region saturated with sodium chloride and potassium chloride, and, in fact, relates to the production of double salts of potassium and magnesium sulfate produced in a system in which sodium chloride may be present, either in part,

or to saturation. The various designations in Fig. 2 are, as obviously set forth, quite similar to those of Fig. 1, the continuous lines referring to equilibrium of salts in the stable field, while the dotted and dashed lines relate to meta-stable conditions.

The preparation and operation of the process is exactly the same with respect to Fig. 2 as with Fig. 1, as described above.

A comparison of Figs. 1 and 2 shows that the line of coexistence of Epsom salts and schoenite in the system saturated with sodium chloride (Fig. 2) will shift towards substantially lower values of magnesium chloride in the conversion solution, as shown, for example, by the line joining the points $M'_{12.5}^0$, M'_{25}^0 , M'_{30}^0 , and M'_{35}^0 . On the other hand, the line of coexistence of leonite and Epsom salt in the system saturated with sodium chloride, as shown in Fig. 2, i.e., the line through the points L'_{25}^0 , L'_{30}^0 , and L'_{35}^0 , is in almost the same position as the corresponding line in the system free from sodium chloride shown in Fig. 1.

The information set forth in Figs. 1 and 2, therefore, obviously may be very advantageously employed in the formation of conversion solutions containing magnesium chloride in a system containing or saturated with sodium chloride. It is seen that the lines of saturation of Epsom salt in both systems (Fig. 1 and Fig. 2) are almost completely similar within the field of operation shown. Thus, if schoenite is sought to be produced from Epsom salt and potassium chloride wherein a sodium chloride saturation is additionally present, the conversion solutions obtained in accordance with this procedure will not contain too much magnesium chloride, and, in fact, will not contain much more than 50 mols of $MgCl_2$ /1,000 mols of H_2O , corresponding to 225–230 g./l. $MgCl_2$ at best. On the other hand, when leonite is produced from Epsom salt and potassium chloride in a system saturated with sodium chloride, the conversion solutions will have a content of magnesium chloride just about equal to that obtained in a similar conversion in a system free entirely from sodium chloride.

The production of double salts and conversion solutions containing substantial quantities of magnesium chloride is basically the same in the system saturated with sodium chloride as in the system free from sodium chloride previously described, with the exception that the tendency of formation of the double sulfate salts is shifted toward lower temperature ranges. Thus, when operating in a system saturated with sodium chloride, and seeking to produce schoenite, a temperature of 35° C. should not be exceeded, while similarly, when seeking to produce leonite, in the system saturated with sodium chloride, a temperature of 50° C. at most should be employed.

Therefore, in the mode of operation when seeking to obtain schoenite and the solution M'_{25}^0 in accordance with Fig. 2, wherein KCl , $NaCl$, schoenite, and Epsom salt will all co-exist at 25° C., the procedure is substantially the same as followed in accordance with the description of Fig. 1 procedure, with the exception that the initial quantities of reactants theoretically required for the conversion are stirred and reacted at about 35° C., and after dissolving all the Epsom salts present, the conversion solution is then cooled down to about 25° C.

Similarly, when seeking to produce leonite and the conversion solution at point L'_{25}^0 in accordance with Fig. 2, the required quantities of potassium chloride, hydrated magnesium sulfate and water theoretically required for the conversion are stirred at a temperature of about 45° C. until all the magnesium sulfate hydrate has been dissolved, and thereafter the mixture is cooled to a temperature of about 25° C., wherein a conversion solution having a composition of magnesium chloride of 57.3 mols/1,000 mols of H_2O , corresponding to about 265 g./l. $MgCl_2$, is produced.

In the various conversions set forth above, in place of

Epsom salt ($MgSO_4 \cdot 7H_2O$), dehydrated Epsom salt or dehydrated kieserite may also be used. In this connection, it has been found that the best mode of operation is to initially stir the quantity of dehydrated magnesium sulfate theoretically required for the conversion at a temperature of say from about 35-40° C. in the aqueous medium, whether it be water or a liquid having a low content of magnesium chloride. The magnesium sulfate is added at this point without the addition of potassium chloride, and this addition increases the temperature of the aqueous medium to approximately 60° C., due to the heat of hydration of magnesium sulfate. Thereafter, a cooling of, for example, to about 45-50° C. is effected, and only at this point is the potassium chloride required for the conversion added, the KCl and $MgSO_4$ thereupon reacting to produce leonite. Thereupon the mixture is cooled down in the prescribed manner to about the temperature for which the initial ingredients have been calculated. The desirability of employing this particular mode of operation when employing dehydrated magnesium sulfate lies in the fact that the heat of hydration upon dissolving the magnesium sulfate causes an increase of temperature to more than 50-55° C., and if the solution were saturated with potassium chloride at this time, there would be a substantial danger of the formation of kainite and a subsequent interference in the proper operation of the procedure. However, when adding the KCl after cooling the initial solution of dehydrated magnesium sulfate in the aqueous medium, there is no danger of the formation of kainite.

In addition, when producing a double sulfate in accordance with either Fig. 1 or Fig. 2, it is possible to obtain even greater values of magnesium chloride in the conversion solution. Thus, after producing and separating the double salt from the conversion solution saturated with Epsom salt, it is possible to further cool the conversion solution in order to precipitate a mixture of Epsom salt and potassium chloride or Epsom salt, potassium chloride, and sodium chloride, as the case may be, in any event, further increasing the content of magnesium chloride in the conversion solution itself.

This further cooling procedure is shown graphically, for example, on Fig. 1, wherein the crystallization path when cooling the conversion solution at point M_{25}^0 from 25-15° C. is shown, the path cutting the Epsom salt isotherm of 15° C. at point E_{15}^0 . As is seen, the conversion solution existing at point E_{15}^0 has a substantially higher content of magnesium chloride, and thus a correspondingly lower content of potassium chloride than the solution at point M_{25}^0 . The mixture of Epsom salt and potassium chloride or Epsom salt, potassium chloride and sodium chloride which will crystallize and separate out due to the cooling of the conversion solution from 25-15° may be returned to a further process for the production of double salt after separation from the conversion solution itself. It is essential, however, in this procedure that, prior to cooling from the desired initial point, i.e., M_{25}^0 in the instant case, the double salt be removed from the conversion solution. Otherwise, as is quite evident from Fig. 1, the double salt produced would react with the magnesium chloride of the conversion solution forming potassium chloride and Epsom salt, and thus in effect reversing the reaction and producing a solution having a low content of magnesium chloride.

The possibility of carrying out the production of the double salt with an aqueous medium initially containing some quantities of magnesium chloride instead of pure water, has previously been mentioned. Such an aqueous medium may be obtained from the production, for example, of potassium sulfate, or a conventional double salt production wherein low magnesium chloride conversion solutions are obtained, or from any other chemical process, and the production of the double salt is preferably effected in such aqueous medium containing small quantities of magnesium chloride.

In addition, a two-stage process of operation in the production of the double sulfate is effected in various two-stage processes, some possibilities of which are as follows:

5 A conventional double sulfate process is initially effected whereby a low-content magnesium chloride conversion solution is obtained and this low-content conversion solution is once again reacted with magnesium sulfate, either hydrated or dehydrated and potassium chloride in order to produce the double salt and the high content $MgCl_2$ conversion solutions.

10 In addition, the two-stage process may be in each stage a production of a double salt in accordance with the invention, as, for example, producing schoenite in the first stage of conversion, and leonite in the second stage. Such an operation is advantageous in that a large portion of the double salt produced is in the form of readily filterable schoenite, and the second stage results in the production of only a small percentage of the total of the double salt produced in the form of the less readily filterable leonite, 15 while the conversion solution itself has an extremely large content of magnesium chloride. If so desired, this procedure may be reversed, and leonite produced in the first stage and schoenite in the second. Further, it is, of course, possible to effect a two-stage reaction wherein either schoenite or leonite is produced exclusively in both stages.

20 When operating with potassium chloride containing substantial quantities of sodium chloride, or if the initial aqueous medium employed contains substantial quantities 25 of sodium chloride, it is always possible that the double salts produced will contain some solid sodium chloride when separated. This will be true in any case where the conversion solution itself cannot absorb and dissolve all 30 of the sodium chloride present in the process. A separation of the double salt produced from solid sodium chloride contained therein will be effected in accordance with various conventional procedures, flotation being preferred in such cases.

35 Where a production of double salt is effected with solutions which contain sodium chloride, but which are not saturated therewith, the prescribed points of operation for the desired conversion solutions may be readily calculated by linear interpolation between the graphs shown in Fig. 1 (no $NaCl$) and Fig. 2 (saturated $NaCl$).

40 For practical purposes it is expedient not to cool the mixtures exactly to that temperature at which the double salt is in a state of equilibrium with Epsom salt and potassium chloride or with Epsom salt, potassium chloride and rock salt, but only to a slightly higher temperature. By this means undercutting of the temperature of equilibrium 45 and consequently the danger of reforming of Epsom salt and potassium chloride from the double salt is definitely avoided at the secondary treatment (filtration etc.).

50 For the production of leonite preferably a range of temperature between about 25-35° C. is chosen, for the production of schoenite one between 20-28° C. Said ranges of temperature may be selected in the presence of $NaCl$ as well as in its absence.

55 Table 1, appearing below, contains the equilibrium data of the various conversion solutions defined and shown in Figs. 1 and 2.

TABLE 1

No.	Designa- tion of solution	Solid phases with which the solutions are in a state of equilibrium

The following examples describe the actual procedure for the production of the double salts along with the various quantitative conditions employed; these examples are illustrative only and are not intended in any way to limit the generic scope of the invention as covered by the appended claims.

Example 1

Production of schoenite in a system free from NaCl, using KCl, Epsom salt and water:

The conversion solution M₂₅ in accordance with Fig. 1 is obtained. The quantitative conditions are calculated according to the following equation: (quantities are indicated as mols or double mols)

The result of this equation is:

$$x=63.2 \\ y=124.7 \\ t=54.7 \\ z=455.3$$

The production of 1t schoenite requires:

0.428tKCl, 1.395t Epsom salt and 0.374t water. The initial products are stirred at a temperature of about 35–40° C., using the quantities indicated until the whole of the Epsom salt has been dissolved. This happens after about half hour. Afterwards the mixture is cooled down to about 25° C. and the schoenite is separated from the adherent liquor by filtration. The K₂O yield is 86.5%, the SO₄ yield is 87.7%. By cooling the mother liquor from 25 to 15° a mixture of Epsom salt and potassium chloride is segregated, which may be used for other charges. The K₂O yield is thereby increased to 89.5, the SO₄ yield to 92.3%.

Example 2

Production of leonite in the system saturated with NaCl, using a mixture of KCl and NaCl, Epsom salt and water; the conversion liquor L₂₅ is obtained in accordance with Fig. 2. The equation for the calculation of the initial quantities is as follows:

Hence the following quantities are required for the production of 1t leonite:

0.491t potassium chloride with 7.0% NaCl,
1.520t Epsom salt and
0.276t water.

The initial products necessary for the conversion are stirred at a temperature of about 45–50° until the whole of the Epsom salt has been dissolved, which happens after half an hour, then the mixture is cooled down to about 25° C. and the leonite is separated from the conversion liquor by filtration. The K₂O yield is 89.1%, the SO₄ yield is 88.4%.

Example 3

As mentioned above, it is suitable to carry out the

process of producing double salt in two stages, as a much more coarsely granulated crystal product is formed, and, furthermore, because the separation of the liquid containing a large amount of magnesium chloride from the double salt is much easier technically at the second concentrated stage. In the example here indicated, a conversion liquor poor in magnesium chloride taken from the first stage of the conversion is to be used. The composition of this liquor which is saturated with NaCl is as follows:

The density of this solution is 1.295. The conversion is to be carried out with Epsom salt and pure potassium chloride, producing leonite. A conversion liquor of the composition L₂₅ (see Fig. 2) is to be formed. The equation for the calculation of the quantitative conditions to be applied is as follows:

The density of this conversion liquor is 1.312. From this equation results:

$$x=0.7157 \\ y=25.36 \\ t=25.09 \\ z=54.95 \\ v=1.46$$

The production of 1t leonite requires:

50 $1.60m^3$ initial liquor,
0.411t KCl and
1.472t Epsom salt.

2.24 m³ of conversion liquor are formed. The leonite 55 contains 1.8% NaCl. The yields of K₂ and of SO₄ for the entire process are exactly the same as in Example 2, but for the part of the process calculated here, the yield of K₂ is 78.2%, that of SO₄ is 77.0%. The conversion is carried out by stirring the initial liquor with the indicated quantities of potassium chloride and Epsom salt at a temperature of about 45–50° C. until the whole of the Epsom salt has been dissolved (about half an hour). Afterwards the mixture is cooled down to about 25° C. and the segregated leonite is separated from the mother liquor by filtration.

Example 4

Production of leonite from potassium chloride containing NaCl and dehydrated magnesium sulfate, using a 70 mother liquor of double sulfate free from NaCl and with a low content of MgCl₂, originating from a conventional process for the production of schoenite:

The composition of the initial liquor is to be:

11

The density of the liquor is 1.266. The equation for the calculation of the quantities to be applied is as follows:

The conversion liquor resulting from this process corresponds to the solution L'_{25} in accordance with Fig. 2; it is therefore saturated with KCl , NaCl , Epsom salt, and leonite at a temperature of 25° C.

From the above equation results:

$$\begin{aligned} x &= 3.28 \\ y &= 5.85 \\ z &= 29.30 \\ v &= 14.07 \\ u &= 0.944 \end{aligned}$$

The initial quantities required for the production of 1 t leonite accordingly are: 3.976 m^3 initial liquor, 0.227 t potassium chloride containing NaCl with 58.3% NaCl , 0.6834 t MgSO_4 (free from water). The quantity of conversion liquor obtained is 3.770 m^3 .

The initial liquor is stirred with the dehydrated magnesium sulfate at about 35–40° C. When the magnesium sulfate is dissolved, the heat of hydration which is set free increases the temperature to about 60° C. After about 15 minutes, the whole of the magnesium sulfate is dissolved. The mixture is then cooled down to about 45–50° C., and the potassium chloride containing sodium chloride is added. The conversion takes about half an hour. Afterwards the mixture is cooled down to a final temperature of 25° C., for which the quantitative conditions have been calculated, and the segregated leonite is separated from the motor liquor by filtration. When this process is carried out under practical conditions, conversion liquors are formed which correspond very closely to the composition of equilibrium solutions as it is theoretically required (see Table 1).

Table 2 indicates a series of conversion solutions produced by practical application, which have been obtained according to the methods illustrated by the above examples.

TABLE 2

No.	Production of—	Contents of NaCl in the conversion liquor	Temperature of conversion		Theoretical equilibrium solution
			Beginning, °C.	End, °C.

The double sulfates of potassium and magnesium are important fertilizer materials. As it is known, several plants do not agree with fertilizers containing chlorine. Therefore it is necessary, to offer to these plants the nutritive material potassium in a form free of chlorine. Compared to potassium sulfate—the common form of potassium fertilizer free of chlorine—the double sulfates

12

of potassium and magnesium, as they are given by schoenite or lenoite, contain in addition magnesium, which is also a valuable nutritive component.

In the claims, when the phrase "at least meta-stable equilibrium" is employed, the same means either meta-stable equilibrium or stable equilibrium.

I claim:

1. A process for the production of double salts of one mol potassium sulfate and one mol magnesium sulfate having chemically bound water with the recovery of a double salt conversion solution having a high magnesium chlorides content, which comprises contacting a member selected from the group consisting of unhydrated magnesium sulfate and the hydrated magnesium sulfates with potassium chloride at a temperature between about 30 and 55° C. in an aqueous medium to thereby precipitate the double sulfate, said contact solution being prepared by addition of said group member and potassium chloride in such quantities to said aqueous medium that in said contact solution there results concentrations which are adjusted to form at a predetermined lower temperature between 20° and 35° C. a solution in a meta-stable equilibrium, thereafter cooling the contact mixture while precipitating further quantities of the double sulfate, at about said predetermined lower temperature and recovering the double sulfate formed and a mother liquid containing at least 220 grams and up to 285 grams of magnesium chloride per liter.

2. A process in accordance with claim 1 in which said potassium chloride and said group member of the hydrated magnesium sulfates are contacted in water at a temperature between about 30 and 45° C., in which cooling is effected to a temperature between about 20 and 28° C. and in which the recovered double sulfate is the $\text{K}_2\text{SO}_4 \cdot \text{MgSO}_4 \cdot 6\text{H}_2\text{O}$ (schoenite).

3. A process in accordance with claim 1 in which said potassium chloride and said group member of the hydrated magnesium sulfates are contacted in water at a temperature between about 45 and 55° C. in which said cooling is effected to a temperature between about 25 and 32° C. and in which the recovered double sulfate is $\text{K}_2\text{SO}_4 \cdot \text{MgSO}_4 \cdot 4\text{H}_2\text{O}$ (leonite).

4. A process in accordance with claim 1 in which said potassium chloride and said group member of the hydrated magnesium sulfates are contacted in water, in the added presence of sodium chloride at a temperature between about 30 and 40° C., in which said cooling is effected to a temperature between about 20 and 28° C. and in which the recovered double sulfate is schoenite.

5. A process in accordance with claim 1 in which said potassium chloride and said group member of the hydrated magnesium sulfates are contacted in water, in the added presence of sodium chloride at a temperature between about 45 and 50° C., in which said cooling is effected to a temperature between about 25 and 32° C., and in which the recovered double sulfate is leonite.

6. A process in accordance with claim 1 in which said potassium chloride and said group member of the hydrated magnesium sulfates are contacted in an aqueous solution having an initial content of magnesium chloride, potassium chloride and magnesium sulfate at a temperature between about 40 and 45° C., in which said cooling is effected to a temperature between about 20 and 28° C., in which the recovered double sulfate is schoenite.

7. A process in accordance with claim 1 in which said potassium chloride and said group member of the hydrated magnesium sulfates are contacted in an aqueous solution having an initial content of magnesium chloride, potassium chloride and magnesium sulfate, at a temperature between about 45 and 55° C., in which said cooling is effected to a temperature between about 25 and 32° C., in which the recovered double sulfate is leonite.

8. A process in accordance with claim 1 in which said potassium chloride and said group member of the hy-

hydrated magnesium sulfates are contacted in an aqueous solution having an initial content of magnesium chloride, potassium chloride and magnesium sulfate, in the added presence of sodium chloride at a temperature between about 30 and 40° C., in which said cooling is effected to a temperature between about 20 and 28° C., and in which the recovered sulfate is schoenite.

9. A process in accordance with claim 1 in which said potassium chloride and said group member of the hydrated magnesium sulfates are contacted in an aqueous solution having an initial content of magnesium chloride, potassium chloride and magnesium sulfate in the added presence of sodium chloride at a temperature between about 45 and 50° C., in which said cooling is effected to a temperature between about 25 and 32° C., and in which the recovered double sulfate is leonite.

10. A process in accordance with claim 1 which includes dissolving unhydrated magnesium sulfate in water at a temperature between about 35 and 40° C., whereby the solution takes on a higher temperature by the heat of hydration of the magnesium sulfate, cooling this solution from this higher temperature to a temperature between about 45 and 55° C. adding then said potassium chloride to the cooled solution whereby leonite will be precipitated, and thereafter cooling the mixture thus obtained further to a temperature between about 25 and 32° C. whereby further quantities of leonite will be precipitated and recovering all the precipitated leonite.

11. A process in accordance with claim 10, in which said initial cooling is effected to a temperature about 45 and 50° C., and which includes the added presence of sodium chloride in the solution of potassium chloride and magnesium sulfate.

12. A process in accordance with claim 1, which includes dissolving unhydrated magnesium sulfate in an aqueous solution having an initial content of magnesium chloride, potassium chloride and magnesium sulfate between about 35 and 40° C., whereby the solution takes on a higher temperature by the heat of hydration of the magnesium sulfate, cooling this solution from said higher temperature between about 45 and 55° C. adding said potassium chloride to cooled solution whereby leonite will be precipitated and cooling the mixture thus obtained to a temperature of about 25 and 32° C. whereby further quantities of leonite will be precipitated and recovering all the precipitated leonite.

13. A process in accordance with claim 12, in which said initial cooling is effected to a temperature between about 45 and 50° C. and which includes the added presence of sodium chloride in said aqueous solution.

14. A process in accordance with claim 1, which includes dissolving unhydrated magnesium sulfate in an aqueous solution having an initial content of magnesium chloride, potassium chloride and magnesium sulfate between about 35 and 40° C., whereby the solution takes on a higher temperature by the heat of hydration of the magnesium sulfate, cooling this solution from said higher temperature to a temperature between about 30 and 45° C. adding said potassium chloride to cooled solution

whereby schoenite will be precipitated and cooling the mixture thus obtained to a temperature of about 20 and 28° C. whereby further quantities of schoenite will be precipitated and recovering all the precipitated schoenite.

5 15. A process in accordance with claim 14, in which said initial cooling is effected to a temperature between about 30 and 45° C. and which includes the added presence of sodium chloride in said aqueous solution.

10 16. A process according to claim 1, which includes as aqueous medium a solution having an initial content of magnesium chloride, potassium chloride and magnesium sulfate, e.g. a conversion solution which contains only a relatively low content of magnesium chloride, produced by the production of double salts of one mol potassium sulfate and one mol magnesium sulfate having chemically bound water by double salt conservation in a well-known manner.

15 17. A process in accordance with claim 16, which includes as aqueous solution a conversion solution which contains no more than about 38-45 mols of magnesium chloride for each thousand moles of water.

20 18. A process in accordance with claim 1, in which, after cooling this contact solution to above said predetermined lower temperature between 20° and 35° C., said double sulfate is separated from said solution at said temperature and which includes further cooling the remaining salt conversion solution to a temperature between about 25 and 10° C. for the precipitation of potassium chloride and a hydrated magnesium sulfate therefrom, separating the precipitated salts from said solution having a substantially higher content of magnesium chloride.

25 19. A process in accordance with claim 18, in which the salts precipitated at a temperature between about 25 and 10° C. are recycled for further use in said process.

30 20. A process in accordance with claim 18, which includes the added presence of sodium chloride in said solution and in which sodium chloride may be precipitated by said further cooling to a temperature between about 25 and 10° C. and removed with said precipitated salts.

35 21. A process in accordance with claim 20, in which the precipitated potassium chloride, the hydrated magnesium sulfate and sodium chloride are recycled for further use in said process.
